ELECTRIC SWITCH

Edwin A. Williams, Jr., Lansdowne, Carl L. Schuck, Philadelphia, and Gerald P. Clute, Drexel Hill, Pa., assignors to General Electric Company, a corporation of New York

Application August 2, 1940, Serial No. 349,846

18 Claims. (Cl. 200—114)

The present invention relates to electric switches, with reference more particularly to improvements in construction of switches of the kind employable as disconnecting devices and having a switching element or blade pivoted for swinging movement to and from a closed position between relatively stationary terminal contacts.

It is common to provide some means for limiting or arresting the opening swinging movement of the switching element in such devices, and for holding the switching element in a predetermined position such as, for example, a position in which the switching element is readily engageable by a switch hook or other operating tool for removal of the element from the switch support. Fixed solid stops are used for this purpose in some forms of disconnecting switch devices. Resilient buffers in the form of spring strips, also have been proposed for the purpose. However, in any case where a switching element of considerable size or weight is employed, there is danger of breakage of the switching element or its support if the switching element is allowed to swing freely into engagement with a solid stop. The danger of breakage of the switching element by engagement with a solid stop, likewise is present in the case of a disconnecting device employing a fused switching element wherein the fuse holder includes a casing constructed of glass, porcelain, or other frangible material. The spring strip form of resilient buffer is unsatisfactory for the reason, among others, that it is difficult to provide a spring strip of practical dimensions, which has the desired resiliency and at the same time is capable of effectively arresting and accurately positioning a large or heavy switching element.

It is one of the objects of the present invention to provide, in a disconnecting switch support, a resilient buffer mechanism which is capable of arresting and maintaining a switching element accurately in a predetermined position, and of absorbing a considerable shock of impact without damage to the switching element or the switch support.

In the case of a switching element pivotally mounted so as to be readily removable from its support, it has been found that swinging of the switching element into engagement with a stop or buffer near one end of the element, may set up forces which tend to cause disengagement of the switching element from its support. The present invention therefore has for another object, the provision of improved latching mechanism for preventing disengagement of a switch-

ing element from its support under such conditions.

A further object is the provision of an improved contact construction and mounting arrangement for disconnecting switch devices and the like.

The invention also has for one of its more specific objects, the provision of a switch support of simple, compact and economical construction, which combines a movable contact and a buffer mechanism in such manner that a common spring means is employable for the dual purpose of biasing the contact into pressure engagement with a switching element pivoted on the support, when the switching element is in closed position, and of absorbing the shock of impact of the switching element against the buffer mechanism when the switching element swings to open position.

Other objects and the details of that which we consider to be novel and our invention, will become apparent from the following description and the appended claims, taken in conjunction with the accompanying drawing wherein:

Fig. 1 shows, in side elevation, an exemplary form of disconnecting switch device embodying our invention;

Fig. 2 is an enlarged side elevation, partially in section, showing details of the hinge, contact, buffer, and latch mechanism at the lower end of the device of Fig. 1;

Fig. 3 is front elevation, partially in section, of the mechanism shown in Fig. 2;

Fig. 4 is a sectional plan view along the line 4—4 of Fig. 2;

Fig. 5 is an exploded view showing, in perspective, the details of construction of certain of the parts of the mechanism shown in Figs. 2-4;

Fig. 6 illustrates the manner of engaging a switch hook with the upper end of the switching element of the device shown in Fig. 1;

Fig. 7 is a side elevation illustrating a modified form of hinge latching mechanism which may be employed in the device of Fig. 1, the switching element being indicated in closed position; and

Fig. 8 shows the mechanism of Fig. 7 with the switching element in an open position.

As will be evident from the ensuing description, various features of the present invention are subject to modification and are suitable for employment in other forms of switch devices. Hence the embodiment shown in the drawing is for purposes of illustration only. In this embodiment the fuse support includes two insulators, 10 and 11, disposed in spaced relationship and bolted or otherwise secured at one end to a suitable base.

12. On the outer end of the upper insulator, 10, there is supported a terminal and contact assembly including a terminal plate 13 having an upwardly projecting extension to which electric line conductors or leads may be secured by clamping devices 14. A contact 15 is rotatably supported on a pin 16 carried by a bracket 17 mounted on terminal plate 13. One or more springs 20 serve to bias contact 15 for rotation in a clockwise direction, as viewed in the drawing, and an adjustable stop screw 21 is provided on the lower end of the contact for limiting its rotation. A flexible braided conductor 22 insures good electric connection between the contact and terminal plate 13. The contact has two outwardly projecting arms 23, one of which may be seen in the drawing, for receiving therebetween and engaging the upper end of a switching element. An outwardly projecting finger 24 also is provided on the contact for a purpose hereinafter described.

On the outer end of lower insulator 11, there is mounted a terminal member 25 which, similarly to terminal plate 13, has an extension to which line conductors or leads may be secured by clamping devices 14. The upper part of terminal member 25 is adapted to serve as a hinge support and has two integrally formed bracket arms 26 disposed in horizontally spaced relationship, and each of which bracket arms has a hook portion designed to provide a trunnion seat 27. The bracket arms serve to support a contact member 30 in accordance with one feature of the present invention. This contact member is generally rectangular and hollow, and is open at the rear as will be seen best from Fig. 5. On opposite sides of the contact member are lugs 31 which engage bearing slots 32, adjacent the tops of the bracket arms, for slidably supporting the contact member between the bracket arms. Hook shaped stops 33 serve to maintain lugs 31 in slots 32 and also to limit outward sliding of the contact member. The contact member is biased outwardly by coiled springs 34 engaged at their outer ends with pins 35 on the inside of the contact member. Although two such springs are employed in the exemplary embodiment illustrated, it will of course be understood that one, or more than two, may be employed if desired. A flexible braided conductor 36, secured at one end to terminal member 25 by a bolt 37 and secured at the other end to contact member 30 by a bolt 38, is provided for insuring good electric connection between the terminal member and contact member.

A buffer member 40 is rotatably supported, intermediate its ends, between bracket arms 26. The support for the buffer member comprises a pivot pin 41 which extends through openings 42 in the opposite sides of the buffer member. The opposite ends of pin 41 are engaged with openings 43 formed respectively in bracket arms 26 at points slightly below and to the rear of trunnion seats 27. Pin 41 is retained in openings 42 by cotter pins 44 or other suitable means. Buffer member 40 is generally L-shaped and is arranged so that one arm thereof projects forwardly and downwardly so as to be in opposed spaced relation to the bottom of a switching element supported by bracket arms 26 in a manner later described. The other arm of the buffer member projects upwardly between the bracket arms and extends behind contact member 30. At the upper end of the buffer member are pins 45 which support the inner ends of springs 34.

Thus the springs are compressed between the buffer member and the contact member, and serve to bias the contact member outwardly while opposing rotation of the buffer member in a clockwise direction, as viewed in the drawing. Counter-clockwise rotation of the buffer member is limited by engagement thereof with terminal member 25, so that the forwardly projecting arm of the buffer member is maintained in the position shown in Figs. 1 and 2.

The present invention may be embodied to advantage in switch supports for the mounting of various forms of switching elements or blades, and it is not intended therefore that the invention be limited to any one particular form of switching element or blade. However, the illustrated exemplary switch support is especially suited for the mounting of switching elements embodying fuse devices having casings constructed of glass, porcelain, or other frangible material. Such a fuse device is indicated at 50 on the drawing. This fuse device may, for example, be of the form shown in U. S. Patent No. 2,188,816, issued January 30, 1940, in the name of W. K. Rankin, and assigned to the same assignee as the present invention. Fuse devices of the form shown in the Rankin patent, are of considerable size and weight, particularly when designed for high current interrupting ratings. They include a fusible element, and insulating support therefor, embedded in a body of sand or granular quartz which is contained in a tubular glass casing such as that indicated at 51 in the drawing. Opposite ends of the glass casing are closed by metallic terminal ferrules 52 which serve for connection of the fuse unit in an electric circuit.

For mounting the fuse holder, comprising casting 51 and ferrules 52, on the previously described switch support, appropriate fittings are applied on the upper and lower ends, respectively, of the fuse holder. The lower fitting comprises a metallic ring 53 clamped on the lower terminal ferrule 52 by means of bolt 54. This ring has rearwardly projecting spaced arms 55, each of which has an integrally formed trunnion 56 for engagement with one of the trunnion seats 27 of the hinge support. When trunnions 56 are engaged with the trunnion seats in the manner shown in Figs. 1 and 2, arms 55 are disposed between bracket arms 26 and respectively on opposite sides of buffer member 40, as will be seen best from Fig. 4. Ring 53 also has two downwardly extending latching parts or projections 57 disposed respectively on opposite sides of the ring, and spaced forwardly from trunnions 56 so as to be just outside of the hook portions of bracket arms 26. If desired, trunnions 56 and projections 57 may comprise elements of a hinge part fixedly mounted on the fuse holder. Also, trunnions 56, instead of being formed integrally with ring 53, may comprise ends of a hinge pin extending between and projecting on opposite sides of arms 55. It will be noted that the axis of the trunnions is offset a substantial distance laterally from the longitudinal axis of the fuse holder so that the weight of the fuse holder tends to cause rotation of the switching element to open position when the trunnions are engaged with the trunnion seats.

The fitting on the upper end of the fuse holder comprises a metallic contact ring 60 clamped on upper terminal ferrule 52 by means of bolt 61. This contact ring has a rounded or semi-spherical surface 62 for engagement by complementary

surfaces on the arms 23 of upper pivoted contact 15. The forward portion of ring 60 has two upwardly projecting lugs 63, one of which may be seen in the drawing, which serve to support a pivot pin 66 upon which a combined handle and latch releasing member 65 is rotatably mounted. Member 65 has a rearwardly projecting finger 66 arranged to extend under finger 24 on contact 15 when the switch element is in closed position. The forward portion of member 65 is in the form of an oval ring 67 adapted to provide an operating eye for engagement by a common form of switch hook or operating tool. On the top of member 65 are two upwardly projecting cylindrical elements 70 and 71 disposed in spaced axial alignment and adapted to provide a socket for receiving one end of the insulating pole 72 of a switch hook in the manner indicated in Fig. 6. Element 71 is open on one side, as indicated at 73, to provide for passage of hook projection 74 when the end of the switch hook is inserted into the socket in the manner later described.

With trunnions 56 engaged with trunnion seats 27, the switching element may be swung into closed position, connected between terminals 13 and 25 as shown in Fig. 1, and is latched in such position by engagement of arms 23 of upper contact 15 with the contact ring 60 on the upper end of the fuse holder. Under these conditions, springs 20 maintain firm pressure engagement between contact arms 23 and contact ring 60, while springs 34 maintain firm pressure engagement between contact member 30 and the lower terminal ferrule 52. When it is desired to swing the switching element to an open position, the hook projection 74 of an operating tool, such as that partially shown in Fig. 6, is engaged with eye 67, and a downward pull is exerted on the operating tool so as to rotate member 65 in a clockwise direction as viewed in the drawing. This causes finger 66 to engage finger 24 and lift contact 15 so as to free the upper end of the fuse holder, whereupon the switching element may be swung to an open position. If the switch hook is maintained in engagement with eye 67, the switching element may be rotated relatively slowly to the open position wherein ring 63 at the bottom of the fuse holder engages the forwardly projecting arm of buffer 40, as shown in the broken lines in Fig. 1. However, if the switch hook accidentally should become disengaged from eye 67, the switching element will swing freely and with considerable force against buffer 40. Under these circumstances, springs 34 effectively absorb the shock of impact and prevent damage to the switching element and the switch support. Trunnions 56 are prevented from jumping out of trunnion seats 27 when the switching element swings into engagement with the buffer, by reason of the fact that projections 57 swing into partially underlying relation to the hook portions of brackets 26 so as to latch the trunnions in the trunnion seats.

When the switching element is moved out of closed position, lugs 31 of contact 30 slide into engagement with stops 33 so that a solid backing is provided for the forward ends of springs 34. Under these conditions the springs are effective to oppose any considerable clockwise rotation of buffer member 40 and serve to position the buffer member accurately for holding the switching element in the desired open position as indicated by the broken lines in Fig. 1 and by the view of the upper end of the switching element in Fig. 6. When the switching element is in the

indicated outwardly inclined position, the end of a switch hook pole 72 may be inserted longitudinally into socket elements 70 and 71, the hook projection 74 being disposed in a position such that it can pass through opening 73 in the forward socket element 71. The switch hook pole then is rotated in a manner to swing projection 74 to a vertical position between elements 70 and 71. This effectively locks the switch hook in engagement with handle 65 so that the switching element may be removed from its support without danger of the switching element dropping off of the switch hook. Removal of the switching element from its support is effected by swinging the switching element slightly upwardly from its extreme open position so as to bring projections 57 into positions which will permit ready disengagement of trunnions 56 from trunnion seats 27. With the switching element removed from the support, fittings or rings 53 and 60 may be removed from the holder of a blown fuse unit and applied to the holder of a new fuse unit, which then may be installed on the support by following the above described operations in the reverse order.

In the modification shown in Figs. 7 and 8, projections 57 are omitted from ring 53 and there is provided, instead, a buffer member 75 which has latching bosses or projections 76 formed thereon intermediate the upper end of the buffer member and its pivotal support 41. Otherwise, the construction and arrangement of the various parts is substantially the same as previously described in connection with the embodiment of Fig. 1. When the switching element is in the closed position, partially shown in Fig. 7, projections or bosses 76 are disposed in retracted positions. When the switching element swings to the open position, partially shown in Fig. 8, and engages buffer 75, the resultant rotation of the buffer in a clockwise direction causes projections 76 to swing into positions overlying portions of the hinge part which includes trunnions 56. Thus the trunnions are blocked against disengagement from the trunnion seats due to such forces as might be set up by swinging of the switching element into engagement with the buffer. For intentional disengagement of the trunnions from the trunnion seats, the switching element is swung upwardly sufficiently to relieve the pressure on the buffer, whereupon springs 34 rotate the buffer and projections 76 backwardly to their retracted positions which permit ready removal of the trunnions from the trunnion seats.

What we claim as new and desire to secure by Letters Patent of the United States is:

1. In an electric switch, a supporting structure having spaced terminals, a switching element pivoted on said structure so as to be swingable to and from closed position between said terminals, a buffer pivoted on said structure and arranged for engagement by said switching element so as to arrest the opening movement of the switching element and hold the latter in a predetermined open position, and spring means arranged to act on said buffer in a manner to resist displacement of the buffer, said spring means being operative to absorb the shock of impact of said switching element against the buffer.

2. In an electric switch, a supporting structure having spaced terminals, a switching element disposed in a closed position between said terminals and pivoted adjacent one end on said

structure so as to be swingable to an open position, a buffer member pivoted on said structure and extending in opposed spaced relation to said one end of the switching element so as to be engageable by said one end of the switching element as the latter swings to open position, and shock absorbing means arranged to oppose displacement of said buffer member when the switching element swings into engagement with said member, said member and shock absorbing means being operative to arrest said switching element in a predetermined open position.

3. In an electric switch, a supporting structure having spaced upper and lower terminals, a switching element extending in a generally upright position connected between said terminals, said element being pivoted on said structure adjacent its lower end so as to be swingable to an open position, the axis of pivoting of said element being offset a substantial distance laterally from the longitudinal axis of said element, a buffer member pivoted on said structure and extending below and in spaced relation to the lower end of said switching element so as to be engageable by the bottom of said element as the latter swings to open position, and spring means arranged to oppose displacement of said buffer member and operative to absorb the shock of impact of said switching element against the buffer member.

4. In an electric switch including a supporting structure having spaced terminals, and a switching element pivoted adjacent one end on said structure for swinging movement into and out of closed position between said terminals; a lever-like member pivoted on said structure adjacent said one end of said switching element for rotation about an axis substantially parallel with the pivotal axis of the switching element, said member being pivoted intermediate its ends, one end of said member being arranged for engagement by said switching element to arrest opening movement of said element when the latter reaches a predetermined open position, and shock-absorbing spring means arranged to act on the other end of said lever-like member in a manner to oppose rotation of said member due to engagement of said switching element with said member.

5. In an electric switch, relatively stationary spaced terminals, a switching element for connection between said terminals, hinge means supporting said element for swinging movement into and out of closed position between said terminals, said hinge means including a pair of hinge bracket arms disposed in spaced relationship and pivot means engaged with said bracket arms, a buffer member rotatably supported on pivot means engaged with said bracket arms, said buffer member arranged for engagement by said switching element so as to arrest opening movement of the switching element, and coiled spring means arranged to act on said buffer member in a manner to absorb the shock of impact of said switching element against the buffer member and to oppose displacement of the buffer member by the switching element.

6. In an electric switch, relatively stationary spaced terminal means, a switching element for cooperation therewith, hinge means supporting said element for swinging movement into and out of connected position, said hinge means including a pair of hinge bracket arms disposed in spaced relationship, said switching element being supported by pivot means engaged with

said bracket arms, a contact member forming part of one of said terminal means, said contact member being disposed generally between said bracket arms and being slidably supported on the bracket arms, and spring means arranged to force said contact member into pressure engagement with cooperative contact means on said switching element.

7. In an electric switch, a supporting structure having spaced terminal means, a switching element connected between said terminal means and pivoted for swinging movement to an open position, one of said terminal means including a movable contact member engageable with cooperative contact means on said switching element, a buffer member movably mounted on said supporting structure and arranged for engagement with said switching element to arrest opening movement of said element, and resilient means arranged to serve the double function of forcing said contact member into pressure engagement with said contact means when the switching element is in closed position and of absorbing the shock of engagement of the switching element with the buffer member when the switching element swings to open position.

8. In an electric switch, a supporting structure having spaced terminal means, a switching element disposed in a closed position between said terminal means and pivoted adjacent one end for swinging movement to an open position, a movable contact member forming part of one of said terminal means and arranged for engagement with cooperative contact means on said switching element, a buffer member pivoted on said structure adjacent said one end of the switching element and engageable with the latter for arresting the opening movement of the switching element, and spring means arranged to force said movable contact member into pressure engagement with said contact means when the switching element is in closed position, the same said spring means being arranged to absorb the shock of impact of said switching element against the buffer member when the switching element swings to open position.

9. In an electric switch, a supporting structure, a switching element pivoted thereon, spaced terminal means carried by said structure for cooperation with said switching element and including a movable contact member arranged for engagement with contact means on the switching element, a buffer member pivoted on said structure and arranged for engagement by said switching element to arrest the opening movement of the latter, and spring means acting between said contact member and said buffer member, said spring means maintaining said contact member in pressure engagement with said contact means when the switching element is in closed position, said spring means also being operative to oppose displacement of said buffer member when said switching element swings into engagement with the buffer member.

10. In an electric switch, a supporting structure, a switching element pivoted thereon, terminal means on said structure including a movable contact member engageable with contact means on said switching element when the latter is in one position, a buffer member pivoted intermediate its ends on said structure, one arm of said buffer member being arranged for engagement by said switching element to arrest the switching element in a second position when said element swings from its first mentioned position,

and one or more springs compressed between said contact member and the other arm of said buffer member so as to maintain the contact member in pressure engagement with said contact means on the switching element when the latter is in its said first mentioned position, said spring or springs also being operative to absorb the shock of impact between said buffer member and switching element when the latter swings to its said second position.

11. In an electric switch, a hinge support including a pair of bracket arms disposed in spaced relationship, a switching element swingably supported adjacent one end by pivot means engaged with said bracket arms, terminal means for co-operation with said switching element including a contact member movably mounted on said hinge support, a front portion of which contact member is arranged to engage said switch element when the latter is in one position, a lever-like member rotatably supported intermediate its ends by pivot means engaged with said bracket arms, one end of said lever-like member being arranged to serve as a buffer for arresting said switching element in a predetermined second position when the switching element swings from its first mentioned position, the other end of said lever-like member extending behind said contact member, and one or more springs compressed between said other arm of the lever-like member and the rear of said contact member.

12. In an electric switch, stationary terminal means, a switching element cooperative therewith, a stationary hinge support including spaced bracket arms having trunnion seats open adjacent the top, the lower end of said switching element including a hinge part having trunnions removably engaged with said seats and pivotally supporting the switching element for swinging movement to open position relative to said terminal means, a movable contact member forming part of said terminal means and engageable with said switching element when the latter is in closed position, a buffer member rotatably supported intermediate its ends on pivot means engaged with said bracket arms, the lower end of said buffer member extending below and in spaced relation to the lower end of said switching element for limiting the opening swinging movement of said element, shock absorbing spring means compressed between said contact member and the upper end of said buffer member for forcing the contact member into pressure engagement with the switching element, and latch means on said buffer member arranged to rotate into overlying relation to a portion of said hinge part when said switching element swings into engagement with the buffer member, so as thereby to prevent disengagement of said trunnions from said trunnion seats.

13. In an electric switch, relatively stationary terminal means, a switching element swingable to and from closed position relative to said terminal means, a support for said element having trunnion seats open adjacent the top, said element having a hinge part including trunnions adjacent its lower end, which said trunnions are removably engaged with said trunnion seats to pivotally support the switching element, and a buffer member pivoted adjacent the lower end of the switching element and operative to limit the opening swinging movement of said element, a part of said buffer member being arranged to swing into a position overlying a portion of said

hinge part in a manner to prevent disengagement of said trunnions from said trunnion seats, said part of the buffer member being swung to said overlying position upon engagement of said switching element with the buffer member.

14. In an electric switch, relatively stationary terminal means, a switching element swingable to and from closed position relative to said terminal means, a support for said element having open trunnion seats, said element having trunnions adjacent one end and removably engaged with said seats so as pivotally to support the switching element, a buffer member movably mounted adjacent said one end of said element and operative to limit the opening swinging movement of said element, and latch means on said buffer member arranged for movement to a blocking position relative to said one end of the switching element in a manner to prevent disengagement of said trunnions from said open trunnion seats, said latch means being moved to said blocking position upon engagement and movement of said buffer member by said switching element.

15. In an electric switch, relatively stationary terminal means, a switching element removably disposed in a closed position relative to said terminal means, hinge means on one end of said switching element and detachably engaged with a relatively stationary hinge support so as pivotally to support said switching element for swinging movement to an open position, a buffer member movably supported adjacent said one end of the switching element so as to be engageable by said element and operative to limit the opening movement of said element, and latch means on said buffer member, which said latch means is arranged to move into a position to prevent disengagement of said hinge means from said hinge support when the switching element swings into engagement with the buffer member.

16. In an electric switch, a support having terminal means thereon, a switching element swingable to and from closed position relative to said terminal means, said element being pivotally supported adjacent one end by cooperative hinge parts respectively on said element and on said support, one of which hinge parts is detachably and pivotally engaged with an open socket portion of the other hinge part, a buffer member pivoted on said support and operative to limit opening movement of said switching element, and a latch part on said buffer member arranged to move into a position to block said one hinge part so as to prevent disengagement thereof from said open socket portion of said other hinge part, said latch part being moved into said blocking position upon engagement and movement of said buffer member by said switching element.

17. In an electric switch relatively stationary terminal means, a movable switching element, hinge means pivotally supporting said switching element for swinging movement to and from closed position relative to said terminal means, said hinge means including spaced bracket arms each having an open trunnion seat, said switching element having trunnions adjacent one end thereof and removably engaged with said trunnion seats, a buffer member adjacent said one end of the switching element for limiting the opening swinging movement of the switching element, and latch parts on said switching element adjacent said one end thereof, which said latch parts are arranged to swing into position for

cooperation with portions of said bracket arms in a manner to prevent disengagement of said trunnions from said open trunnion seats when the switching element swings into engagement with said buffer member.

18. In an electric switch, relatively stationary terminal means, a movable switching element, hinge means pivotally supporting said switching element for swinging movement to and from closed position relative to said terminal means, said hinge means including spaced bracket arms having hook portions providing trunnion seats open adjacent the top, said switching element having trunnions adjacent its lower end remov-

ably engaged with said trunnion seats, a buffer member adjacent the lower end of the switching element for limiting the opening swinging movement, and latch parts on said switching element adjacent said trunnions, which said latch parts are swingable into positions at least partially underlying said hook portions of the bracket arms so as to prevent disengagement of said trunnions from said trunnion seats when the switching element swings into engagement with said buffer member.
